Application filed August 31, 1898. Serial No. 689,958. Term of patent 14 years.

To all whom it may concern:

Be it known that I, WILLIAM KEIL, a citizen of the United States, residing at the city of New York, borough of Manhattan, in the county of New York and State of New York, have invented and produced a new and original Design for a Fabric, of which the following is a specification, reference being had to the accompanying drawing, forming a part thereof, in which is represented a plan view of a section of fabric embodying the features of my design.

The design consists of a body A and a border B. The body A presents alternate lozenge and plain stripes a and a' , which merge into triangular panels a^2 , which panels are decorated with open threadwork and fanciful figures. The border B is separated from the body A by a bar b , and the border is decorated by floral figures b' , the figures in adjacent rows facing in opposite directions. The border is further ornamented by a skirting b^2 , representing open threadwork and fanciful figures.

The leading feature of the design consists in a striped body and panels, into which the stripes merge, and in floral decorations for the border and a skirting for the same. 25

I claim—

1. In a fabric, the design for the body A 30 herein shown and described.
2. In a fabric, the design for the border B herein shown and described.
